UNITED STATES PATENT OFFICE.

HENRY E. BRUMMEL, OF BOONVILLE, MISSOURI.

CLOSURE-OPERATING MEANS.

Application filed September 24, 1921. Serial No. 502,909.

To all whom it may concern:

Be it known that I, HENRY E. BRUMMEL, a citizen of the United States, residing at Boonville, in the county of Cooper and State 5 of Missouri, have invented certain new and useful Improvements in Closure-Operating Means, of which the following is a specification, reference being had to the accompanying drawings.

10 This invention relates to closure operating means, and has for its object to provide means of this character adapted for connection to a door or gate to permit opening and closing of the door or gate at a distance.

15 It is another object of the invention to provide means of this character including a novel actuating member which when operated causes closing and opening of the closure member, said member being movable vertically.

20 It is also an object of the invention to provide means of this character for actuating a double closure member, such as two doors, means being connected to one door for 25 actuation by an operator, and means connected to said door and to the remaining door for operating the remaining door upon movement of the first mentioned means.

25 It is still a further object of the invention 30 to provide a device of this character including a foldable actuating member which when the door or closure member is opened is disposed in its extended position, and when the door is closed, in its folded position, said member being also connected to means for operating the latches of the closure member and adapted to prevent accidental closing of the door or closure member.

40 With these and other objects in view, the invention consists in the improved construction and arrangement of parts to be herein-after more particularly described, fully claimed and illustrated in the accompanying drawings, in which:—

Figure 1 is a view in elevation of the pair of closure members closed showing the position of the actuating member;

Figure 2 is a top plan view of the doors 50 in their open positions;

Figure 3 is a perspective view of one of the actuating members;

Figure 4 is a perspective view of the main actuating member;

Figure 5 is a view in elevation of the 55 structure shown in Figure 2;

Figure 6 is an interior elevation of the closure members showing the arrangement of the latches;

Figure 7 is a side elevation of one of the 60 closure members in its open position; and

Figure 8 is a fragmentary sectional view 65 showing the connection of the main actuating member to the closure member and latches.

It is of course obvious that this mechanism can be applied to all forms of closure members, including a gate or door. For the purpose of illustration, doors are used. In

70 this embodiment of the invention, 5 and 6 designate the walls of a building, and 7 and 8 the closure members or doors. These doors are the type used on garages, warehouses, and for closing large door ways. The doors are hinged to the wall in the 75 usual manner. The door 8 is provided with a relatively large opening or slot 9, while secured to the inner surface of the door 8 adjacent the slot 9 is a bearing block 10 from which a pin 11 projects, the purpose 80 of which will be hereinafter described.

To open and close the door 8, a novel actuating member 12 is provided, said member comprising a pair of strips 13 and 14 which are hinged at one of their ends to each other. 85 Hinged to the strip 13 at its opposite end is a plate 15, while hinged to the opposite end of the strip 14 is a plate 16, the plate 15 having an opening 17, while the plate 16 is provided 90 with a slot 18. Projecting from the strip 14 adjacent the connection of the strips to each other is an eye member 19, the purpose of which will be hereinafter described.

Positioned adjacent the hinged connection of the closure member or door 8 to the wall 6 and in spaced relation to the wall of the building is a standard 20 which may be secured in any suitable manner, while extending from the standard 20 and connected to the wall 6 is a supporting member 21. Projecting from the top of the standard 20 is a bar 22 from which pulleys 23 and 24 depend.

The plate 15 of the actuating or hinge 105 member 12 is pivotally connected to the standard 20 by means of a pin extending through the opening 17, the actuating mem-

ber being connected to the support 21 adjacent the standard 20. It will be noted that the supporting member 21 is disposed below the slot 9 so as to prevent the actuating member from being disposed on a dead center. The plate 16 is adapted to extend through the slot 9 the pin 11 being passed through the slot 18 of the plate 16, the plate 16 being prevented from disengagement by means of a fastening pin 25 passed through the pin 11. As shown in Figure 1, the strips 13 and 14 are disposed in angular relation to each other so that the actuating member will readily respond when it is desired to open the doors or closure members. Projecting from the end of the plate 16 is an eye 26 to which a wire or cable 27 is connected. Pivoted to the inner face of the door 8 adjacent the slot 9 is a bell crank lever 28 to the end 29 of which the cable 27 is connected. Extending from the ends 29 and 30 of the bell crank lever are cables 31 and 32, the cable 31 being connected to the intermediate portion of a latch member 33 which is pivoted to the upper portion of the door 8 as at 34, while the cable 32 is pivotally connected to the intermediate portion of a latch member 35 which is likewise pivotally connected to the lower portion of the door as at 36. To hold the doors 7 and 8 in their closed positions, a pair of substantially Z-shaped keepers 37 and 38 are provided, the keeper 37 having its bill disposed downwardly so that upon upward movement of the latch member 33 the end of the keeper 37 will be disposed within the keeper. The keeper 38 has its bill disposed upwardly so that upon downward movement of the latch member 35 the end of the latch will be received by the keeper. Operation of the latches is accomplished simultaneously.

In order to permit both closure members or doors 7 and 8 to be opened simultaneously there is provided an auxiliary actuating member 39 comprising a pair of strips 40 and 41, said strips being hinged at one of their ends to each other. The opposite end of the strip 40 is reduced and threaded to provide a stem adapted to extend through an opening provided in the upper corner portion of the door 8. Nuts 42 and 43 are used to hold the strip 40 rigid.

Pivoted to the opposite end of the strip 41 is a plate 44 which is adapted to be secured to the upper corner portion of the door 7. A brace 45 is connected at one end of the door 8 and at its opposite end to the strip 40 so as to maintain the strip 40 substantially at right angles to the door 8 at all times and to prevent independent movement of said strip. The strip 41, however, is intended to oscillate. The strips 40 and 41 are of a length sufficient to prevent the central pivotal connection of the actuating

member 39 from being disposed on a dead center so that there is a slight bulge in the actuating member 39 when the doors 7 and 8 are disposed at the limit of their open movement as shown in Figure 2.

When the doors are in their closed positions, as shown in Figures 2 and 6, the strips 13 and 14 of the actuating member 12 are disposed in angular relation, while the strips 40 and 41 of the actuating member 30 are disposed substantially parallel to each other, or in other words, V-shaped. Connected to the eye member 19 is a ring 45 to which a pair of cables 46 and 47 are connected. These cables extend over the pulleys 23 and 24. The cable 47 extends through the wall 6 to the exterior of the building while the cable 46 extends inwardly of the building. When either of the cables 46 or 47 is pulled, the strips 13 and 14 are moved substantially upwardly, the strip 13 at the same time moving toward the standard 20, while the strip 14 is moving in a horizontal position.

This also causes sliding movement of the plate 15 on the block 10, which movement causes the cable or wire 27 to oscillate the bell crank lever 28 thereby moving the latch members 33 and 34 toward each other and disengaging the same from the keepers 37 and 38 whereby the doors are unlatched. Continued pull on the cable will cause the strip 14 to move toward and beyond the standard 20. At the same time, the plates 15 and 16 are swung on their respective supports so as to position the actuating member 12 at right angles to the door. In this way the strip 13 is gradually moved beneath the strip 14 to fold the actuating member 12 as shown in Figures 2, 5 and 7.

As soon as the doors 7 and 8 start to move the strip 40 of the actuating member 39 moves with the door 8 as it is rigidly connected. This causes pivotal movement of the strip 41 thereby moving the door 7 similar to the door 8.

To close the doors 7 and 8 the desired cable is again pulled so as to raise the strips 13 and 14 to the position shown in Figure 5 and in view of the fact that the pulleys 23 and 24 are disposed inwardly of the connection of the strips 13 and 14 to each other, said strips will be moved toward and beyond the standard 20 thereby causing the door 8 to swing away from the standard 20. Continued pull upon the cable will cause the connection of the strips 13 and 14 to pass beyond the center of gravity and then through the medium of gravity swing the door 8 to its closed position, whereupon the strips of the actuating member 12 will be disposed as shown in Figure 1. This movement causes the strip 40 of the actuating member 39 to swing inwardly, thereby substantially folding said actuating member and

moving the door 7 to its closed position. The closing movement of the actuating member 12 causes sliding movement of the plate 16 on the block 10 thereby oscillating the 5 bell crank lever 28 and permitting the latch members 33 and 35 to engage their respective keepers.

From the foregoing it will be readily seen that this invention provides a novel and 10 simple closure operating mechanism that is capable of being operated by anyone. In addition to this the novel position of the strips 13 and 14 of the actuating member 12 prevents accidental closing of, the doors 15 when in their open positions thereby eliminating the necessity of separate props. Furthermore, both of the cables may be used for opening and closing the doors and both doors are swung to their open and closed 20 positions by a slight pull on one of the cables.

What is claimed is:—

1. In combination with a closure member having an opening therethrough, a bracket 25 carried by said closure adjacent the opening, latch means carried by the closure member, a hinge member comprising a pair of strips hinged at one of their ends to each other, a plate hinged to each of the opposite ends of 30 the strips, one of said plates being slidably mounted on the bracket and movable through said opening and operatively connected to the latch means, the remaining

plate being pivoted to a support adjacent the closure member and adapted to oscillate on 35 the support upon folding movement of the strips relative to each other, and actuating means connected to one of said strips closely adjacent the hinged connection of the strips to each other.

2. In combination with a closure member having an opening therethrough, a bracket carried by said closure adjacent the opening, latch means carried by the closure member, a hinge member comprising a pair of strips 45 hinged at one of their ends to each other, a plate hinged to each of the opposite ends of the strips, one of said plates being slidably mounted on the bracket and movable through said opening and operatively connected to the latch means, the remaining 50 plate being pivoted to a support adjacent the closure member, the strip of the hinge member to which the last mentioned plate is connected being normally disposed in angular 55 relation to the remaining strip of the hinge member, said remaining strip being normally disposed substantially in alignment with the plate mounted on the bracket, and actuating means connected to the last 60 mentioned strip for folding said strips one upon the other and upon the plate pivoted to the support.

In testimony whereof I hereunto affix my signature.

HENRY E. BRUMMEL.
